UNITED STATES PATENT OFFICE.

GEORGE G. SCHELTER, OF ROCHESTER, NEW YORK, ASSIGNOR TO FITZ-EMPIRE DOUBLE PIVOT LAST COMPANY, OF AUBURN, MAINE, A CORPORATION OF MAINE.

LAST.

1,562,779.

Specification of Letters Patent. Patented Mar. 29, 1921.

Application filed August 8, 1919. Serial No. 316,219.

To all whom it may concern:

Be it known that I, GEORGE G. SCHELTER, a citizen of the United States, residing at Rochester, in the county of Monroe and 5 State of New York, have invented certain Improvements in Lasts, of which the following description, in connection with the accompanying drawings, is a specification, like reference characters on the drawings indicating like parts in the several figures.

This invention relates to lasts for making boots and shoes and in particular to collapsible lasts. It has been found advisable to provide lasts of this type with some sort of 15 "locking means" or mechanism to hold their parts in desired positions. When the last is in the shoe it should be held in the normal, or extended position with sufficient rigidity to avoid any danger of its collapse during 20 the shoemaking operations. The shoe is inverted during many such operations and also during the last pulling operation, and if a positive lock is used, it is therefore necessary to move it, and in general to hold it, 25 out of operative position at the time of removing the last. This necessitates some appliance in connection with the jack used in withdrawing the last. Inasmuch as it is sometimes necessary to withdraw the last at 30 other times than the regular last pulling, such a last lock requires special jacks located more or less widely over the shoe factory, the jacks being so specialized as to render them 35 inconvenient or impractical for use in connection with lasts of other makes. Shoe manufacturers are unwilling to equip their factories with such special jacks, and this has mitigated against the use of hinge lasts having positive locks. Hinge lasts with 40 lock which are not positive are widely used, because the lasts can be collapsed and withdrawn on any jack, but such lasts sometimes meet with criticism because of their lack of rigidity.

45 The present invention provides a novel construction of last having a positive lock, the locking element of which can be moved and held out of positive locking position so that accidental return thereto is avoided. 50 The positively locked condition can thus be terminated with the last in any convenient position in the operator's hands and will so remain, so that no special jack is required for operating the last.

55 It is an important object of the present

invention to provide a hinge last with a positive lock requiring no special tools for its manipulation, and accordingly a feature of the invention resides in a last having a positive lock arranged to be rendered im- 60 positive at will. The last can thus be collapsed on the ordinary jack, and removed without difficulty, at the same time affording the desired rigidity and without sacrificing any of the advantages of known lasts. 65

Stated from another viewpoint, the invention provides a collapsible last having a positive and an impositive locking means, and provision for rendering one of said means operative and the other inoperative 70 at will. The last illustrated has a locking member with two surfaces arranged to cooperate with an abutment in turn, one for positive and the other for impositive locking, and means for shifting one of said surfaces into operative position in place of the other.

A further important feature of the invention resides in provision for rendering the last always positively locked after being 80 straightened or extended. This is accomplished, in the form shown, by an automatic means for throwing the lock shifting means out of operative position, preferably as the last collapses, but in any case before the last 85 reaches extended position.

Another feature resides in a construction whereby the last parts are relatively displaced slightly from normal extended position when the last is impositively locked. 90

These and other features of the invention, comprising various arrangements and combinations of parts, will be understood from the following description of a preferred embodiment of the invention, selected for illustrative purposes, and shown in the drawings in which,

Figure 1 shows the last in extended position.

Fig. 2 shows the last after the lock has 100 been rendered impositive.

Fig. 3 shows the last partially collapsed.

Fig. 4 shows the last completely collapsed.

Fig. 5 is a cross-section on the line 5—5 of Fig. 1.

The last shown is a collapsible last having a heel part and forepart separated by secant faces and united by hinge mechanism of any desired forms. I have found the last invented by John C. Schelter which is disclosed 110

and claimed in application Serial No. 267,757, filed Dec. 21, 1918, to be admirably adapted for the embodiment of my invention, but the invention, though shown as applied thereto, is not to be understood as limited to this specific form of last.

The cut between the heel part and the forepart is vertically directed from the sole for a short distance into the body of the last as shown at 10; from there it slopes to the front, as shown at 12, until it reaches approximately the center of the last. At this point the heel part and forepart separate, the cut going upwardly and inclining slightly to the rear upon the heel part, as shown at 14, and forward, as shown at 16, upon the forepart at a somewhat greater slope than the portion 12, as far as a point about three-quarters of the height of the last and from there nearly vertically, as shown at 18, to the top of the cone. The fore and heel parts are united by two links 20 and 22. These links are preferably formed in duplicate with the locking mechanism between them as shown in Fig. 5. The link 20 is formed of two separate parts 20^a and 20^b and the lower link 22 being similarly formed of two parts 22^a and 22^b. These links are joined to the last parts by rivets 24, 26, 28 and 30, passing through the links and seated in the last parts. All the foregoing structure is substantially as shown in the application of John C. Schelter above referred to.

The rivet 26 acts as an abutment for the locking means. The locking member is shown as a flat steel plate 32 pivoted at one end upon the rivet 30 between the plates 22^a and 22^b. It has at its other end a downwardly projecting lug 34 arranged to engage a spring 36 seated in one of the last parts (as illustrated, the forepart), and has on the upper surface of the same end a projection 38 arranged to coöperate with the pin 26. This projection 38 has two operating surfaces, one of which, 40, is substantially perpendicular to the radius vector 42 extending thereto from the rivet 30, and the other of which, 44, is at an acute angle with said radius vector. The portion 40 when in engagement with the rivet 26, as shown in Fig. 1, will positively lock the last in extended position since the reaction between the pin 26 and the locking member is substantially perpendicular to the surface 40. But if the locking member is moved and held in the position shown in Fig. 2, with the surface 44 in engagement with the pin 26, a collapsing pressure will cause a relative slipping motion between the pin and the surface 44 which will permit the last to be collapsed by pressure alone.

This movement of the member 32 may be contrived in various ways, but I have found the following described construction advan-

tageous. A member 46 is pivoted, preferably upon the pin 24, and has a hole 48 conveniently located in it to receive a ball 50 and a spring 52. The member 46 is located between members 20^a and 20^b and the spring-pressed ball frictionally holds the member 46 in any position in which it happens to be. The member 46 has on its lower surface a lug 54 and a lug 56. The lug 54, as shown in Fig. 1, normally rests on the upper surface of the member 32. The member 46 extends up into the opening 57 between the last parts so as to be easily accessible to the operator. When displaced by the operator it forces down the member 32 so that the surface 44 is exchanged for the surface 40 in contact with the pin 46. At the same time, the lug 56 slips down behind the projection 38, and wedges the member 32 firmly in the position shown in Fig. 2. At the same time, the stress exerted by the spring 36 rotates the links 20 and 22 and the lock member slightly so as to cause a slight relative displacement of the last parts, all of which is clearly shown in Fig. 2. This displacement serves as a warning to the operator in case the last is in a shoe, that the last is impositively locked.

The last is now collapsible by pressure alone and can be removed from the shoe by the simple and well-known expedient of putting the last upon an upwardly extending jack pin and manipulating the last and shoe in the ordinary manner. This will cause the last to pass through the position shown in Fig. 3 to that shown in Fig. 4. The member 32 is preferably provided with an upstanding lug 58 which engages the member 46 behind the lug 54 as the last moves from the Fig. 3 position to the completely collapsed position shown in Fig. 4. The reaction between the lugs 58 and 54 throws the member 46 upwardly, as shown in Fig. 4, so that when the last is brought back to extended position the member 46, being frictionally held by the ball 50, will not fall back with the lug 56 engaging behind the lug 38. The last, therefore, when extended will always come to positively locked position.

It is obvious that the duplicated hinge link construction is not material to the present invention but it makes the last stronger and better able to resist twisting strains of the leveling operation.

It is now clear that my novel last while providing a positive lock and thereby furnishing ideal conditions for machine shoemaking can be unlocked without the use of any special tools or without requiring a special jack. The member 46 can be easily moved by the operator's finger to render the last impositively locked and the last can be collapsed by pressure alone upon any ordi-

nary jack pin. The last therefore combines all the advantages of a positive lock with those of an impositive lock.

Having described my invention, what I claim as new and desire to secure by Letters Patent of the United States is:—

1. In a last, separate fore and heel parts, bonding mechanism joining said parts constructed and arranged to permit the collapse of the last, a normally positive lock, and means for rendering said lock impositive at will.
2. In a last, separate fore and heel parts, bonding mechanism joining said parts constructed and arranged to permit the collapse of the last, a positive locking means and an impositive locking means, constructed and arranged for substitution of one of said means for the other, at will.
3. In a last, separate fore and heel parts, bonding mechanism joining said parts constructed and arranged to permit the collapse of the last, a member on one of said last parts constructed and arranged to engage the other last part in two relations, to hold the last rigidly extended or to permit collapse by pressure, respectively.
4. In a last, separate fore and heel parts, bonding mechanism joining said parts constructed and arranged to permit the collapse of the last, a member on one of said last parts constructed and arranged to engage the other last part in two relations, to hold the last rigidly extended or to permit collapse by pressure, respectively, there being provision for changing from the former of said relations to the latter at will.
5. In a last, separate fore and heel parts, bonding mechanism joining said parts constructed and arranged to permit the collapse of the last, a member on one of said last parts constructed and arranged to engage the other last part in two relations to hold the last rigidly extended or to permit collapse by pressure, respectively, and a member actuatable to change one of said relations to the other at will.
6. In a last, separate fore and heel parts, bonding mechanism joining said parts constructed and arranged to permit the collapse of the last, a member on one of said last parts constructed and arranged to engage the other last part substantially perpendicularly to effect a positive lock or substantially acutely to permit collapse of the last under pressure.
7. In a last, separate fore and heel parts, bonding mechanism joining said parts constructed and arranged to permit the collapse of the last, a member on one of said last parts constructed and arranged to engage the other last part substantially perpendicularly to effect a positive lock or substantially acutely to permit collapse of the last under pressure, there being provision for changing from the former of said relations to the latter at will.
8. In a last, separate fore and heel parts, bonding mechanism joining said parts constructed and arranged to permit the collapse of the last, a member on one of said last parts constructed and arranged to engage the other last part substantially perpendicularly to effect a positive lock or substantially acutely to permit collapse of the last under pressure, and a member actuatable to change one of said relations to the other at will.
9. In a last, separate fore and heel parts, bonding mechanism joining said parts constructed and arranged to permit the collapse of the last, an abutment on one last part, a swinging member on the other last part having two surfaces either of which is swingable into engagement with said abutment, respectively, to hold the last positively or impositively locked against collapse.
10. In a last, separate fore and heel parts, bonding mechanism joining said parts constructed and arranged to permit the collapse of the last, an abutment on one last part, a swinging member on the other last part having two surfaces either of which is swingable into engagement with said abutment, respectively, to hold the last positively or impositively locked against collapse, and a member constructed and arranged to move the swinging member to exchange the surface in contact with the abutment.
11. In a last, separate fore and heel parts, bonding mechanism joining said parts constructed and arranged to permit the collapse of the last, an abutment on one last part, a swinging member on the other last part having a surface substantially at right angles to its radius vector to the axis of swing and a second surface making an acute angle with said radius vector.
12. In a last, separate fore and heel parts, bonding mechanism joining said parts constructed and arranged to permit the collapse of the last, an abutment on one last part, a swinging member on the other last part having a surface substantially at right angles to its radius vector to the axis of swing and a second surface making an acute angle with said radius vector, and a member constructed and arranged to move said swinging member to move one surface out of and the other into engagement with said abutment.
13. In a last, separate fore and heel parts, bonding mechanism joining said parts constructed and arranged to permit the collapse of the last, an abutment on one last part, a swinging member on the other last part having a surface substantially at right angles to its radius vector to the axis of swing and a second surface making an acute angle with said radius vector, and a member constructed and arranged to move said swinging member to move one surface out

of and the other into engagement with said abutment and to lock the swinging member in the second position.

14. In a last, separate fore and heel parts, bonding mechanism joining said parts constructed and arranged to permit the collapse of the last, a member on one of said last parts constructed and arranged to engage the other last part in two relations to hold the last rigidly extended or to permit collapse by pressure, respectively, and a member actuatable to change one of said relations to the other at will, and means for moving said second-named member to inoperative position as the last is collapsed.

15. In a last, separate fore and heel parts, bonding mechanism joining said parts constructed and arranged to permit the collapse of the last, a positive locking means, an impositive locking means permitting collapse of the last by pressure only, said positive locking means going automatically into operation as the last is extended after collapsing.

16. In a last, separate fore and heel parts, bonding mechanism joining said parts constructed and arranged to permit the collapse of the last, a locking member having positive and impositive locking positions, a member accessible to the operator for moving the locking member from positive to impositive locking position to permit collapse of the last by pressure, there being provision for moving said accessible member into inoperative position before the last reaches extended position after collapse.

17. In a last, separate fore and heel parts, bonding mechanism joining said parts constructed and arranged to permit the collapse of the last, a locking member having positive and impositive locking positions, a member

accessible to the operator for moving the locking member from positive to impositive locking position, to permit collapse of the last by pressure, there being provision for moving said accessible member into inoperative position as the last is collapsed.

18. In a last, separate fore and heel parts, bonding mechanism joining said parts constructed and arranged to permit the collapse of the last, a normally positive lock, and means for rendering said lock impositive at will, said last parts being slightly relatively displaced from extended position when impositively locked.

19. A locking member for a collapsible last having a portion constructed and arranged to engage an abutment in one last part and a portion constructed and arranged to engage an operating member for moving said member to inoperative position as the last collapses.

20. In a last, separate fore and heel parts, a mechanism between said parts comprising bonding members constructed and arranged to permit the collapse of the last, and comprising a locking member arranged to lock the last positively against collapse, the locking member being further arranged to move into operative engagement with an element of the said mechanism upon being displaced from positive locking position, whereby it is held against accidental return to said positive locking position, and to be moved out of operative engagement with the said element by the operation of collapsing the last, whereby the last, when extended, may be again positively locked.

In testimony whereof I have signed my name to this specification.

GEORGE G. SCHELTER.
